UNITED STATES PATENT OFFICE

99,858

DESIGN FOR A TEXTILE FABRIC

Curt Erwin Forstmann, Montclair, N. J.

Application October 5, 1935, Serial No. 58,858

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The design pattern consists of parallel weft-wise elevated spaced stripes, alternate stripes each showing two closely arranged parallel coarse threads overcast by fine stitches, and the other alternate stripes being characterized by merging rows of undifferentiating stitches in which no coarse parallel threads appear.

I claim:

The ornamental design for a textile fabric as shown and described.

CURT ERWIN FORSTMANN.
